1 Claim

ABSTRACT OF THE DISCLOSURE

The invention concerns a circuit element comprising a transparent or translucent chamber filled with an ionizable gas, such as neon. Electrodes are disposed within the chamber, and include starting electrodes for initiating ionization, and holding electrodes for continuing ionization. The chamber is resiliently mounted with external contacts so that conduction may be stopped by pressing on the chamber.

The present invention relates to a circuit element for energizing a load during a time interval longer than the duration of an initiating signal, and more particularly to such an element additionally capable of functioning as an annunciator or indicator.

Conventional prior art elements for performing these functions include a relay with holding contacts, and a thyratron tube. Each of these prior art devices is bulky and expensive. According to the present invention a small chamber of an ionizable gas is arranged with suitable exterior contacts and structure so as to be capable of performing both functions, at a considerable savings in cost and complexity.

The primary object of the invention is to provide a novel circuit element for maintaining current flow for a time interval longer than that of an initiating signal.

A further object is to provide a circuit element of the above character which functions as an annunciator.

Other objects of the invention will in part be obvious and will in part appear hereinafter.

For a more complete understanding of the nature and objects of the invention, reference should be had to the following detailed description taken in connection with the accompanying drawings, in which:

FIGURE 1 is a schematic vertical sectional view of a first embodiment of the invention, and

FIGURE 2 is a similar schematic vertical sectional view of a second embodiment of the invention.

Referring now to FIGURE 1, the circuit element according to the present invention includes a base member 20 defining a cylindrical bore 22 having an open upper end. An insulating chamber 24, filled with an ionizable gas such as neon, is slideably mounted in bore 22. Preferably chamber 24 is formed of glass or other light-permeable material. A first electrode 26 is mounted within chamber 24 and is supported by terminal 28 extending through lower wall 30 of chamber 24. The lower external end of terminal 28 is offset to form the movable contact of a normally closed switch. Fixed contact 32 of the normally closed switch has one end offset and interposed between the lower end of terminal 28 and chamber 24, and extends through the bottom wall 34 of base 20. A second electrode 36 within chamber 24 is connected through bottom wall 30 to a resilient spring member 38 interposed between walls 30 and 34. A second spring 40 is likewise

2

interposed between walls 30 and 34, and is connected to terminal 42 within chamber 24. An electrical resistance heating wire 44 connects electrode 36 and terminal 42.

Chamber 24 and movable contact 28 are therefore resiliently urged by springs 38 and 40 upwardly toward the open end of bore 22, urging movable contact 28 into engagement with fixed contact 32. A low voltage source 46 is connected between first contact 32 and spring 38, while a high voltage source 48 is connected between spring 38 and spring 40 by a series switch 50.

When chamber 24 is filled with a suitable ionizable gas, such as neon, argon, or the like, ionization of the gas may be initiated by momentarily closing switch 50, thus energizing heater 44. The voltage supplied by source 46 should be below the threshold or ionization potential of the gas in chamber 24, at the particular gas pressure and electrode spacing employed, but should be higher than the holding potential (the potential required to maintain conduction through the gas once conduction is attained through other means). Once conduction has been initiated between electrodes 26 and 36, it will be maintained until the normally closed switch (formed by elements 28 and 32) is opened. This may be accomplished by manually pressing chamber 24 into bore 22, temporarily interrupting contact between elements 28 and 32.

FIGURE 2 illustrates a variation wherein the ionizable gas is confined in a separate glow tube 52 mounted inside chamber 24. Energization of heater 44 from source 48 initiates conduction through tube 52, which continues until current flow is interrupted by depressing chamber 24.

Having described our invention what we claim as new and desire to secure by Letters Patent is:

1. An ionization latch, comprising in combination:
  - (a) a housing defining a cylindrical bore having an open end,
  - (b) an insulating chamber filled with an inert gas, said chamber being slidably mounted in said bore, at least the portion of said insulating chamber nearest said open end being formed of a light-permeable material,
  - (c) a first electrode in said chamber connected to an external contact movable with said chamber,
  - (d) a fixed contact mounted in said housing adjacent said external contact and interposed between said external contact and said open end,
  - (e) means resiliently urging said chamber and said external contact toward said open end whereby said external contact is normally urged into engagement with said fixed contact,
  - (f) a further electrode in said chamber,
  - (g) means for applying to said fixed contact and to said further electrode a voltage higher than the holding potential and less than the ionizing potential between said electrodes,
  - (h) and means for initiating discharge between said electrodes.
